UNITED STATES PATENT OFFICE

124,765

DESIGN FOR A TEXTILE FABRIC OR SIMILAR ARTICLE

Paul Reiman, New York, N. Y.

Application November 14, 1940, Serial No. 96,585

Term of patent 3½ years

To all whom it may concern:

Be it known that Paul Reiman, a citizen of the United States, residing in the city, county, and State of New York, has invented a new, original, and ornamental Design for a Textile Fabric or Similar Article, of which the following is a specification, reference being had to the accompanying drawing, forming part thereof.

The figure of the drawing is a plan view of a textile fabric or similar article showing my new design.

The figure shows the entire width of the fabric from selvage to selvage and the design unit is repeated in regular fashion along the length thereof.

I claim:

The ornamental design for a textile fabric or similar article, as shown and described.

PAUL REIMAN.
